(57) **CLAIM**

The ornamental design for a toy roadway tile, as shown and described.

DESCRIPTION

FIG. 1 is a perspective view of a toy roadway tile;
FIG. 2 is a left-side view of the invention;
FIG. 3 is a right-side view of the invention;
FIG. 4 is a front elevation view of the invention;
FIG. 5 is a rear elevation view of invention;
FIG. 6 is a top plan view of the invention; and,
FIG. 7 is a bottom plan view of the invention.

1 Claim, 5 Drawing Sheets
